ANTENNA DECOUPLING BY MEANS OF A LOSSY DIELECTRIC SLAB

John G. Hoffman, Riverside, Calif., assignor to the United States of America as represented by the Secretary of the Navy

Filed July 27, 1964, Ser. No. 385,525
5 Claims. (Cl. 343—771)

The invention herein described may be manufactured and used by or for the Government of the United States of America for governmental purposes without the payment of any royalties thereon or therefor.

The present invention relates to flush mounted antennas and more particularly to a means for reducing the coupling between flush mounted antennas in a common conducting ground plane.

The coupling between flush mounted antennas (i.e. slots) has been found to be much different than with simple horn antennas, and also quite critical in terms of dielectric constant, dielectric loss tangent and thickness of the dielectric. The method of decoupling, used with horn antennas, based upon absorbing the incident electric field of the feed transmit horn is unsuccessful when used with flush mounted slot antennas. Old methods of obtaining decoupling in flush mounted slot antennas involved the use of chokes in the vicinity of the antennas, but this had the detrimental effect of producing deterioration in the antennas' radiation patterns.

The decoupling technique of the instant invention involves using a thin slab of dielectric mounted between flush mounted slot type receive and slot type transmit antennas to increase the surface impedance and to dissipate the energy coupled into the dielectric.

It is an object of the invention to provide a means for reducing the coupling between flush mounted antennas in a common ground plane.

Another object of the invention is to provide a decoupling means for flush mounted slot antennas by the use of a lossy dielectric slab.

A further object of the invention is to provide a high degree of decoupling between slot antenna arrays without causing deterioration in the antenna's radiation patterns.

Other objects and many of the attendant advantages of this invention will become readily appreciated as the same becomes better understood by reference to the following detailed description when considered in connection with the accompanying drawing wherein:

The figure of drawing is a diagrammatic representation of a pair of slot antennas decoupled by means of a lossy dielectric mounted therebetween on the surface of a cylindrical vehicle.

As shown in the figure of drawing, a transmit slot-type antenna 10 and a receive slot-type antenna 12 are mounted in a conducting cylindrical surface 14 with a thin slab 16 of lossy dielectric mounted between the two antennas. The antennas may be mounted in either curved or flat conducting ground surfaces. The dielectric slab 16 can be mounted flush with the antenna slots, or on either side of the conducting ground surface 14.

2

The coupling mechanism between two slot antennas mounted in a conducting ground plane is by means of a surface mode. It has been found that the degree of coupling of this surface mode to the conducting surface is dependent upon the surface impedance of the ground plane. For a highly conducting ground plane this mode is loosely coupled to the surface, and consequently, any obstructions in the ground plane will not cause appreciable decoupling between the two antennas. Therefore, the purpose of this invention is to increase the surface impedance in order to couple the mode into the surface very tightly and then dissipate the energy in the lossy dielectric. The lossy dielectric slab 16 has a two-fold purpose: to increase the surface impedance of the ground plane, and to dissipate the energy coupled into the dielectric.

A high degree of decoupling between slot antenna arrays is obtainable in the instant case without causing deterioration in the antenna's radiation patterns by the lossy dielectric slab 16.

Obviously many modifications and variations of the present invention are possible in the light of the above teachings. It is therefore to be understood that within the scope of the appended claims the invention may be practiced otherwise than as specifically described.

What is claimed is:

1. An antenna decoupling system for reducing the coupling between flush mounted slot-type antennas without producing deterioration in the antennas' radiation patterns comprising:

- (a) a common conducting ground plane,
- (b) a pair of longitudinal slot-type antennas flush mounted in said common conducting ground plane,
- (c) a thin slab of lossy dielectric mounted on said common conducting ground plane between said flush mounted antennas,
- (d) said lossy dielectric slab increasing the surface impedance of the ground plane between the antennas and dissipating energy coupled into the dielectric.

2. A device as in claim 1 wherein said common conducting ground plane is a curved rather than planar surface.

3. A device as in claim 1 wherein said dielectric slab is mounted flush with the surface of said slot-type antennas.

4. A device as in claim 1 wherein an array of flush mounted antennas are used.

5. A device as in claim 1 wherein said pair of longitudinal slot-type antennas are parallel mounted.
